UNITED STATES PATENT OFFICE.

ANDREW J. DINKEL, OF CLARINDA, IOWA, ASSIGNOR OF ONE-HALF TO HARRY C. HARTMAN, OF CLARINDA, IOWA.

SPARK-PLUG.

1,239,365.

Specification of Letters Patent.

Patented Sept. 4, 1917.

Application filed February 18, 1917. Serial No. 148,982.

To all whom it may concern:

Be it known that I, ANDREW J. DINKEL, a citizen of the United States, and a resident of Clarinda, in the county of Page and State 5 of Iowa, have invented a new and Improved Spark-Plug, of which the following is a full, clear, and exact description.

This invention relates to spark plugs for internal combustion engines, and has for its 10 general objects to improve the construction and operation whereby carbon or soot is prevented from collecting on the sparking points, one of these sparking points or electrodes being a freely movable body which 15 is at all times maintained a constant distance from the fixed electrode for the purpose of maintaining the spark gap constant.

A more specific object of the invention is the provision of a fixed central electrode 20 with a movable electrode in the form of a ring which is mounted on a circular support concentric with the sparking point of the fixed electrode.

Still another object is the provision of a 25 cleaning device associated with the freely movable electrode element to move therewith for keeping the sparking surface thereof clean and for preventing the accumulation of soot in the shell or body of the spark 30 plug at a point adjacent the inner end of the porcelain bushing.

With such objects in view, and others which will appear as the description proceeds, the invention comprises various novel 35 features of construction and arrangement of parts which will be set forth with particularity in the following description and claims appended hereto.

In the accompanying drawing, which 40 illustrates one embodiment of the invention and wherein similar characters of reference indicate corresponding parts in all the views,

Figure 1 is a central vertical section of a 45 spark plug;

Fig. 2 is a side view with a portion in section, the section being taken at right-angles to the plane of the section in Fig. 1;

Figs. 3 and 4 are longitudinal sections of 50 a modified form of spark plug, one of the sections being taken on a plane at right angles to the plane of the other section;

Fig. 5 is a bottom plan view of Fig. 4; and

Fig. 6 is a perspective view of the cleaning device.

Referring to the drawing, 1 designates the metallic shell or body of the spark plug, in which is clamped in the usual manner the porcelain bushing 2 that contains the central rod 3, the inner end or tip 4 of which constitutes the fixed electrode of the spark plug. The other electrode is in the form of a ring 5 which is grounded on the shell 1 and supported by a bail 6. This bail is 60 semi-circular and has its ends formed into journals 7 disposed in alinement and engaging in bearings 8 carried by the shell or body 1, the axis of the pivots or journals being in a line which passes through the 70 center of the rounded or hemispherical electrode tip 4. The bail is concentric with the center of the tip 4, so that at all times the movable electrode will be a constant distance from the fixed electrode, whereby 75 the spark gap is constant. As the bail is movable and as the electrode 5 is movable, the latter is constantly presenting a new 80 surface to the fixed electrode and as the position of the movable electrode changes 85 the sparking point on the fixed electrode automatically shifts. With the electrodes constructed in this manner the collection of soot or carbon on the sparking points is 90 reduced to a minimum.

In the construction shown in Figs. 3 to 6 inclusive the movable electrode 5' is supported on a fixed ring 9 which is concentric with the fixed electrode 4', the ring being 95 in a plane above the tip of the fixed electrode, so that the sparking surface will be on the side of the fixed electrode. The supporting ring 9 being concentric with the fixed electrode, the spark gap between the periphery of the movable electrode and the 100 fixed electrode will be constant. Associated with the movable electrode 5' is a cleaning device 10 which has a pair of bifurcations 11 at its lower end so as to straddle the movable electrode and straddle the ring 9, whereby the cleaning device is movably supported. The vibration of the engine causes the movable electrode and cleaning device to work around the ring 9 in one

direction or the other. The cleaning device at the point 12 will keep the periphery of the ring 5' clean. The upper end of the device 10 lies within the body 1' of the spark plug and between it and the inner end of the porcelain bushing 2', so that the movement of the cleaning device will keep soot or carbon from accumulating at the points where the device contacts with the body or bushing. The movable electrode may be of any desired peripheral shape to insure effective sparking.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A spark plug including a fixed electrode, a movable electrode in the form of a ring, and a support on which the movable electrode is free to rotate or move laterally while being maintained a fixed distance from the fixed electrode.

2. A spark plug including a central fixed electrode, a curved support concentric with

the electrode, and a movable electrode mounted on the support for lateral and rotatable movement thereon.

3. A spark plug including a metallic shell 40 or body, a bushing therein, a fixed electrode, a movable electrode mounted to maintain a fixed length of spark gap, and a cleaning device movable with the movable electrode.

4. In a spark plug, the combination of a 45 metallic body or shell, a central electrode in the shell, an insulating bushing supporting the central electrode, a metallic support grounded on the shell and having a curved portion concentric with the fixed electrode, 50 a bodily movable electrode on the support, a cleaning device movably mounted on the support and associated with the movable electrode, said cleaning device having a portion extending into the body or shell to clean 55 the same.

5. In a spark plug, the combination of a metallic body or shell, a central electrode in the shell, an insulating bushing supporting the central electrode, a metallic support 60 grounded on the shell and having a curved portion concentric with the fixed electrode, a bodily movable electrode on the support, and a cleaning device movably mounted on 65 the support and associated with the movable electrode, said cleaning device having a portion extending into the body or shell to clean the same, said cleaning device having another portion making a cleaning engagement with the movable electrode.

ANDREW J. DINKEL.
